UNITED STATES PATENT OFFICE.

GOMMAIRE RACHARD, OF NEW YORK, N. Y.

TWIN-HEAD BORING BAR.

Application filed October 13, 1922. Serial No. 594,414.

To all whom it may concern:

Be it known that I, GOMMAIRE RACHARD, whose post-office address is 504 East 17th Street, New York, N. Y., a subject of the King of Belgium, residing at New York, in the county and State of New York, have invented certain new and useful Improvements in Twin-Head Boring Bars; and I do hereby declare the following to be a full, clear, and exact description of the invention, such as will enable others skilled in the art to which it appertains to make and use the same, reference being had to the accompanying drawings, and to characters of reference marked thereon, which form a part of this application.

My invention relates to a novel construction of boring bar or holder for boring tools for use in connection with lathes, boring mills, shapers and other metal working machines.

The invention has for its principal object to provide a simple strong, and durable construction of boring bar or holder, provided at its free end with a novel arrangement and inter-association of tool seating sockets or openings, whereby the tool may be selectively positioned to project at a desired given angle relative to the axis of bar or holder, together with a simply and easily operated means for rigidly clamping the tool in a selected position; all to the end that the cutting tool may be rigidly supported and held against undue vibration, and yet subject, by simple manipulation of the clamping devices, to interchangeable disposition without necessity of removing the bar or holder from its set or fixed relation to the machine in which it is being used, while nevertheless rendering it very easy to bring the cutting edge of the tool in desired relation to the work being done.

With the above and other objects, not at this time more particularly set forth, in view, the invention consists in the novel boring bar or holder for boring tools; and the invention also consists in the novel arrangements and combinations of the various devices and parts, as well as in the details of the construction of the same, all of which will be fully described in the following specification, and then defined in the appended claims.

The invention is clearly illustrated in the accompanying drawings:—

Figure 1 is a plan elevation of the bar or

holder with the tool and clamping elements removed; Figure 2 is a side view of the same; Figure 3 is a vertical longitudinal section through the bar or holder, with the clamping elements in place, but the tool removed; Figure 4 is a side view of the clamping rod; Figure 5 is a fragmentary longitudinal section of the bar or holder, showing the tool secured thereto to project at an angle of 45 degrees, and associated with said view is a forward end elevation of the bar with the tool so disposed; and Figure 6 is a similar fragmentary longitudinal section of the bar or holder, showing the tool secured thereto to project at an angle of 90 degrees and associated in this view is a forward end elevation of the bar with the tool so disposed.

Similar characters of reference are employed in all of the above described views, to indicate corresponding parts.

Referring to the drawings, the reference character *a* indicates the main body of the bar or holder. This main body is tubular in form, so that a central longitudinal clamp rod *b* may extend forwardly therethrough from its rear end. The rear end of the bore of said tubular main body *a* is provided with internal screw threads *k* into which is threaded a set screw *d* to engage the rear end of said clamp rod *b*. The forward end of said clamp rod is provided with two faces, the one face *i* being disposed at 90 degrees relative to the longitudinal axis of the rod, and the other face *j* being disposed at 45 degrees relative to the longitudinal axis of the rod. Adjacent to its free end said clamp rod *b* is provided on one side with a plane or flat face *c* which is engaged by the end of keeper screw *e* that is tapped through the wall of the bar or holder *a*, so that said keeper screw *e*, while not binding the clamp rod *b* against longitudinal movement or play, will prevent, however, any turning of the same so as to result in its displacement from proper assembled relation to the bar or holder *a*, and the tool receiving openings or seats of the latter which are subsequently to be described. Said keeper screw *e* also serves to prevent outward displacement or escape of the clamp rod *b* through the outer or forward open end of the bar or holder *a* when the tool is removed from the latter. Provided in the wall of said bar or holder *a*, adjacent to its outer or forward end and at one side thereof, is

a rectangular opening or seat *g*, the forward and rear sides of which are disposed at right angles or at 90 degrees relative to the longitudinal axis of the bar or holder *a*. In like manner, provided in the wall of said bar or holder *a*, on the same side with the opening or seat *g* but spaced rearwardly therefrom, is a second rectangular opening or seat *h*, the forward and rear sides of which are disposed at 45 degree angles relative to the longitudinal axis of the bar or holder *a*. Formed in the wall of said bar or holder *a*, on the opposite side from that in which said openings or seats *g* and *h* are disposed, is a third rectangular opening or seat *f* which is opposed to the opening or seat *g* and also to the opening or seat *h*. The forward and rear sides of said opening or seat *f* are disposed at 45 degree angles relative to the longitudinal axis of the bar or holder *a*, and the forward side thereof is in alinement with the forward side of the opening or seat *h*, while the rear side thereof is in alinement with the rear side 25 of the opening or seat *h*. The inner transverse edge portion of the forward side of the opening or seat *f* is alined with the forward side of the opening or seat *g*, while the outer transverse edge portion of said forward side of the opening or seat *f* is alined with the forward side of the opening or seat *h*, thus providing a 90 degree seating face in the same plane as said forward side of the opening or seat *g*, and a 30 45 degree seating face in the same plane as said side of the opening or seat *h*. The outer transverse edge of the rear side of the opening or seat *f* is alined with the rear side of the opening or seat *g*. From the 35 above description of the location, arrangement and interrelation of said openings or seats *g*, *h* and *f*, it will be evident that a suitable cutting tool *E* may be selectively arranged in operative relation to the bar or holder *a* for projection therefrom at a 45 degree angle, by passing the tool through the opening or seat *h* so that its forward end passes outwardly between the angular forward and rear sides of the opening or 40 seat *f*, as shown in Figure 5; or the tool may be arranged for projection from the side of the bar or holder *a* at a 90 degree angle, by passing the tool through the opening or seat *g*, so that its forward end passes 45 outwardly through the opening or seat *f*, between the inner transverse edge portion of the forward side and the outer transverse edge of the rear side of said latter opening or seat, as shown in Figure 6.

When the cutting tool is disposed for a 45 degree angle of projection, the set screw *d* is screwed home against the rear end of the clamp rod *b*, thereby thrusting the latter forward to carry its face *j* against the body 50 of the tool *E*, thus firmly clamping the same

against movement relative to the bar or holder *a*, as is also illustrated in Figure 5.

When the cutting tool is disposed for a 90 degree angle of projection, the set screw *d* is screwed home against the rear end of the clamp rod *b*, thereby thrusting the latter forward to carry its face *i* against the body of the tool *E*, thus firmly clamping the latter in such position, as is also illustrated in Figure 6 of the drawings.

It will be quite clear, that if it is desired to change the position of the tool *E* from one angle of projection to the other, such change may be effected without disturbing the connection of the bar or holder *a* in the machine in which the same is mounted. All that it is necessary to do is to relax the set-screw *d* so that the tool *E* is relieved from the bite of the clamp-rod *b*, and then withdraw the tool *E* from the one position and again insert the same in the other position relative to the openings or seats *g*, *h* and *f*, as the case may be, and then again thrust forward the clamp-rod *b* to biting or clamping position.

From the above description it will be apparent that my invention provides a very simple arrangement whereby the tool may be selectively associated with the bar or holder at a desired angle of projection, and then firmly and rigidly held against undue vibration during the cutting operations by the novel arrangement and cooperation of the tool supporting and clamping elements of the device.

Having thus described my invention, I claim:-

1. In a device of the kind described, a main body having a longitudinal bore internally threaded at its rearward end, the wall of said main body being provided at one side adjacent to its forward end with tool receiving openings spaced longitudinally one from the other, one of said openings having spaced forward and rear sides disposed at an angle of 90 degrees relative to the longitudinal axis of the main body, the second of said openings having spaced forward and rear sides disposed at an angle of 45 degrees relative to the longitudinal axis of the main body, the wall of said main body being further provided at its opposite side with a third tool receiving opening having spaced forward and rear sides disposed at an angle of 45 degrees relative to the longitudinal axis of the main body and alined respectively with the forward and rear sides of the second opening, said third opening being so disposed that the inner transverse edge of its forward side and the outer transverse edge of its rear side are respectively alined opposite the forward and rear sides of said first opening, a clamp bar extending forwardly through the bore of said main body, and a set screw threaded in

the rear end of said main body to thrust said clamp bar into operative holding engagement with a tool selectively positioned relative to said tool receiving openings.

- 5 2. In a device of the kind described, a main body having a longitudinal bore internally threaded at its rearward end, the wall of said main body being provided at one side adjacent to its forward end with tool receiving openings spaced longitudinally one from the other, one of said openings having spaced forward and rear sides disposed at an angle of 90 degrees relative to the longitudinal axis of the main body, the 10 second of said openings having spaced forward and rear sides disposed at an angle of 45 degrees relative to the longitudinal axis of the main body, the wall of said main body being further provided at its opposite side with a third tool receiving opening having spaced forward and rear sides disposed at an angle of 45 degrees relative to the longitudinal axis of the main body and alined respectively with the forward and rear sides 15 of the second opening, said third opening being so disposed that the inner transverse edge of its forward side of the outer transverse edge of its rear side are respectively alined opposite the forward and rear sides 20 of said first opening, a clamp bar extending forwardly through the bore of said main body, a set screw threaded in the rear end of said main body to thrust said clamp bar into operative holding engagement with a tool selectively positioned relative to said tool receiving openings, the forward biting end of said clamp bar having two tool engaging faces, one of said faces being in a plane at an angle of 90 degrees to the longitudinal axis of said main body, and the other of said faces being in a plane 25 at an angle of 45 degrees to the longitudinal axis of said main body, and means to prevent rotation of said clamp bar in said main body.
- 25 4. In a device of the kind described, a tubular main body having in its wall at one side adjacent to its forward end tool receiving openings, one of which permits a tool to pass therethrough at right angles to the longitudinal axis of said main body while the other permits a tool to pass therethrough at a lesser angle, said main body having in its wall at the opposite side a third tool receiving opening so shaped and disposed as to permit the extension of a tool therethrough when extending from either of said first mentioned openings, and means for clamping a tool when selectively extended through said tool receiving openings.
- 30 5. In a device of the kind described, a tubular main body having in its wall at one side adjacent to its forward end tool receiving openings, one of which permits a tool to pass therethrough at right angles to the longitudinal axis of said main body while the other permits a tool to pass therethrough at a lesser angle, said main body having in its wall at the opposite side a third tool receiving opening so shaped and disposed as to permit the extension of a tool therethrough when extending from either of said first mentioned openings, and means for clamping a tool when selectively extended through said tool receiving openings, comprising a clamp-bar extending forwardly through the bore of said tubular main body, and a set screw threaded into the rear end of said main body to actuate said clamp-bar.
- 35 6. In a device of the kind described, a main body having a longitudinal bore internally threaded at its rearward end, the wall of said main body being provided at one side adjacent to its forward end with tool receiving openings spaced longitudinally one from the other, one of said openings having spaced forward and rear sides disposed at an angle of 90 degrees relative to the longitudinal axis of the main body, the second of said openings having spaced forward and rear sides disposed at an angle of 45 degrees relative to the longitudinal axis of the main body, the wall of said main body being further provided at its opposite side with a third tool receiving opening 40 having spaced forward and rear sides dis-
